UNITED STATES PATENT OFFICE.

OTTO A. FREDERICKSON, OF WETHERSFIELD, CONNECTICUT, ASSIGNOR TO THE AMERICAN WIREMOLD COMPANY, OF HARTFORD, CONNECTICUT, A CORPORATION OF CONNECTICUT.

BRAIDING MACHINE.

Application filed May 15, 1925. Serial No. 30,468.

To all whom it may concern:

Be it known that I, OTTO A. FREDERICKSON, a citizen of the United States, residing at Wethersfield, county of Hartford, and

5 State of Connecticut, have invented an Improvement in Braiding Machines, of which the following description, in connection with the accompanying drawings, is a specification, like characters on the drawings

10 representing like parts.

This invention relates to braiding machines, and more particularly to means for supporting and driving the inner yarn carriers.

15 Braiding machines as heretofore commonly constructed are provided with a revolving outer drum which supports the outer yarn carriers and also the outer ends

20 of the inner yarn carriers, and the inner yarn carriers are driven in one direction while the outer drum and the outer yarn carriers are rotated in the opposite direction. This revolving outer drum is commonly provided with vertical slots thru

25 which the outer strands of yarn pass inwardly to the braiding point, and in the inner face of the revolving drum is formed an annular groove or slide-way adapted to support the outer end of the inner yarn carriers, and this groove crosses the vertical slots.

30 These braiding machines as commonly constructed heretofore are provided with a pair of rollers mounted upon the outer end of each inner yarn carrier to rotate in a horizontal plane and in position to extend into the annular groove of the revolving

35 drum to support the outer end of the inner carriers, and another roller is commonly rotatably secured to the outer portion of each carrier to rotate in a vertical plane in position to be engaged by a driver that pushes the inner carriers around their path of travel.

40 One illustration of a braiding machine employing these features which are now extensively used is found in the patent to Anker Petersen, No. 1,241,550, granted October 2, 1917.

45 Braiding machines constructed in the manner above indicated, and as shown in said patent, work fairly satisfactorily when driven at a moderate speed, but they do not work well when driven at high speed, 50 because, when the braiding machine is op-

erated at high speed the centrifugal force of the inner carriers causes the rollers at the outer end of the inner carriers to press hard against the inner wall of the annular groove of the rotating drum, and since this groove is intersected by the vertical yarn receiving slots, the rollers rotating in the annular groove produce a thumping or hammering effect each time they pass over a vertical slot. Furthermore, it is difficult 60 to lubricate these rollers properly without permitting the oil to soil the outer yarn passing thru the vertical slots, and the bearings of these wheels are likely to stick so that the wheels fail to rotate and drag, or 65 the bearings become worn so that the wheels run too loosely.

70 Another objection to these braiding machines now in use resides in the means for pushing the inner carriers around their path of travel and which consists of a pair of rollers, one journaled upon the inner yarn carrier and the other upon the rotating driver frame. These cooperating rollers pinch each strand of outer yarn that passes 75 under the inner carrier, and since one of the cooperating rollers lies considerably below the other, as shown in the patent above mentioned, the pushing force that drives an inner carrier is in an upwardly inclined direction and is much greater than would be 80 required if the axis of the cooperating rolls were in the same horizontal plane. It therefore follows that the pinching force upon the outer strands of yarn is much greater 85 than the horizontal propelling force exerted upon the inner carrier.

90 When a pair of driving rollers are employed one upon the inner carrier and the other upon the rotating driver, as just described, it is possible for the inner carrier to race ahead of the driver when the speed of the braiding machine is being checked, and to prevent this it has been proposed heretofore to provide the driver frame with a second roller positioned in front of the first to prevent overrunning, 95 but this increases the number of rollers that engage the outer strands of yarn as the inner and outer carriers travel in opposite 100 directions.

105 Having the above matters in mind, the present invention relates to means for supporting and driving the inner carriers, so that the hammering effect and other objec- 110

tionable features incident to the use of rollers that extend into the annular groove of the rotating drum are avoided, and, in accordance with the present invention, the 5 inner carriers are driven about their path of travel without overrunning and without the outer strands of yarn being pinched by the driving means.

One important feature of the present invention resides in a rotating driving frame 10 having driving disks, and in blocks secured to the inner yarn carriers and each having a bearing surface that rests upon and partly embraces a driving disk so that these disks 15 serve to support and drive the inner carriers. The driving disks are preferably provided with a number of notches thru which the outer strands of yarn may pass between the block and disk without being 20 pinched, and the disks are preferably positively rotated within the bearing blocks so that different strands of yarn enter the different notches, thus distributing the wearing effect of the yarn thruout a number of 25 notches.

The notched driving disk and cooperating bearing block of the present invention may be constructed of various materials, but it is found they work extremely well when the 30 disk is formed of hardened steel and the block is formed of oil treated wood. This provides a self lubricating bearing between the disk and block which will supply just enough oil to permit the disk to rotate 35 smoothly against the block; and another feature of the invention therefore resides in an oil treated wooden block mounted upon the inner carrier in position to be engaged by the driving disk.

Another important feature of the invention 40 resides in a shoe or in shoes extending from the outer end of each inner carrier into sliding engagement with an annular bearing surface, or an annular groove, formed 45 in the inner face of the revolving outer drum. These shoes serve to take the outward thrust of the inner carriers due to 50 centrifugal force and to retain the inner carriers in place, and it is found that these 55 shoes work most satisfactorily when formed of wood treated with oil or soaked in oil. The wooden shoes not only slide freely and smoothly along the annular bearing surface of the drum and over the vertical slots, but it is unnecessary to lubricate the shoes that have been soaked in oil.

This is important because if oil is applied 60 to the annular bearing surface, it will accumulate where the vertical slots intersect the annular bearing surface and will soil the outer strands of yarn passing thru these slots; the lubricant will also cause particles of lint to adhere to the annular bearing surface. By forming the shoes of oil soaked 65 wood, in accordance with the present inven-

tion, the heat produced by friction upon the shoe will serve to drive out of the wood just enough oil to supply the required lubricant, without supplying enough oil to soil the outer strands of yarn.

Other features of the invention and novel combination of parts in addition to the above will be hereinafter described in connection with the accompanying drawings which illustrate good, practical forms of the invention.

In the drawings:

Fig. 1 is a perspective view of a portion of a braiding machine provided with an inner yarn carrier that is supported and driven 80 in accordance with the present invention.

Fig. 2 is a vertical sectional view thru a portion of a braiding machine showing a modification of the invention.

Fig. 3 is a vertical sectional view thru a portion of a braiding machine showing another modification of the invention; and

Fig. 4 is a vertical sectional view thru the braiding machine of Fig. 1.

The novel means of the present invention 90 for supporting and driving the inner yarn carriers may be used in connection with various types of braiding machines which for the most part are of the usual or any preferred construction. In the braiding machine shown the operating parts are supported by a frame or table 10 that may be provided with supporting legs not shown, and the table 10 is provided with inwardly 95 extending arms 11 which support at their inner ends a fixed vertically disposed drum 12, which drum is shown as having an internal diameter much larger than the flexible core *a* that passes upwardly thru the 100 drum to the braiding point.

Supported from the central fixed drum 12 is the revolving outer drum 13 having a laterally inwardly extending flange portion 14 which connects the outer portion of the drum to its hub 15. A ring 16 which supports the outer yarn carriers is mounted upon the upper end of the revolving outer drum 13, and this ring is shown as insulated from the drum 13 by non-conducting material 17. The outer yarn masses 18 are supported by 115 brackets 19 secured to the ring 16.

A raceway for the inner yarn carriers is formed between the revolving outer drum 13 and the fixed drum 12, and the inner carriers 20 that travel in this raceway are shown as comprising an elongated hollow frame 120 adapted to receive the inner yarn mass 21, and in the construction shown in Figs. 1 and 4 each inner yarn carrier is provided with a roller 22 at its inner end that is rotatably secured to the carrier by a screw 23, and these rollers 22 rest upon an annular race-way or track 24 formed upon the fixed disk or spider 25 the hub of which is rigidly 125 secured to the upper portion of the fixed 130

drum 12. At the outer end of each inner carrier 20 is provided a shoe or a pair of shoes 26 that slidably engage an annular bearing surface formed in the inner face of the revolving outer drum 13, and these shoes, which form an important part of the present invention, will be hereinafter more fully described.

During the operation of the braiding machine the outer yarn carriers are rotated in one direction about the axis of the braiding machine, and the inner yarn carriers are rotated in the opposite direction, and the means shown for driving the outer and inner yarn carriers will now be described. Between the hub 15 of the revolving outer drum and the fixed drum 12 is rotatably mounted an intermediate drum 27 which is rotatably supported by an anti-friction bearing 28, shown as mounted between a laterally extending annular flange portion 29 of the intermediate drum, and the laterally extending annular flange portion 30 of the fixed drum 12. The anti-friction bearing 28 is shown as formed of balls the lower portions of which lie in an annular groove formed in the flange 30, and the upper portions of which extend into an annular groove formed in the lower face of the flange 29.

The revolving outer drum 13 is rotatably mounted upon and is supported by the intermediate drum 27, and the intermediate drum 27 is provided with a lower laterally extending flange portion 31 provided with an upwardly extending annular wall 32 at the upper end of which is formed a ball raceway 33 adapted to receive the anti-friction balls 34 that extend into an annular groove formed in the lower face of the flange portion 14 of the revolving outer drum. The arrangement is such that while the intermediate drum 27 rotatably supports the revolving outer drum 13, these two drums are free to rotate in opposite directions. In order to drive these two drums in opposite directions the laterally extending portion 14 of the revolving outer drum has secured to its lower face a ring gear 35 which is secured to the portion 14 by bolts 36, and the laterally extending portion 31 of the intermediate drum 27 is provided with a ring gear 37 positioned below the ring gear 35 and rigidly secured to the flange portion 31 by bolts 38. A bevel gear not shown engages the teeth of the ring gears 35 and 37 and drives the gears and the parts to which they are secured in opposite directions.

The operating mechanism so far described is illustrated to make clear the features of the invention which will now be set forth, but it will be understood that the novel features about to be described may be used in connection with various types of braiding machines other than that shown.

The driving means for the inner carriers 20 consist of a driver frame 39 having a hub 40 which is rigidly secured to the upper portion of the intermediate drum 27 by any suitable securing means such as a key 41, 70 and this driver frame is provided with a number of driving disks which serve to drive the inner yarn carriers. In the embodiment of the invention shown in Figs. 1 and 4, the driving disks 42 serve to drive 75 the inner yarn carriers and also to support the outer ends of these carriers, and the driving disks are therefore shown as positioned upon the driving frame so that they lie below the outer end portion of the inner 80 yarn carriers. Each inner yarn carrier 20 is provided with a block 43 secured to its under face and each block is formed with a concave bearing surface 44 that is adapted to receive and rest upon the upper curved 85 surface of a driving disk 42, the arrangement being such that the travel of each inner yarn carrier is positively controlled by a driving disk 42 and the cooperation between the disk and block is such that the carrier 90 cannot race ahead of its particular driving disk when the braiding machine is being suddenly stopped.

As is usual the inner yarn carriers pass alternately over and under the strands of 95 yarn 45 led downwardly from the different outer yarn masses 18 to the traversing arms 46 and from these arms thru vertical slots 47 of the revolving outer drum to the braiding point 48. In order to prevent these outer strands of yarn 45 from being injured as they pass between a driving disk 42 and its cooperating block 43, each disk 42 is provided with a number of yarn receiving slots 49 and the disks 42 are positively rotated at such a speed that one of the notches 49 will always be in position to receive an outer strand of yarn as the inner carrier passes over the same and will cause the shoe 43 to pass over the strand of yarn without 100 injuring the same. In order to drive the disks 42 at the proper speed, each disk is rigidly secured to a horizontally extending shaft journaled within a bearing block 50 secured to the driver frame 39, and at the 105 inner end of each of these shafts is rigidly secured a bevel gear 51 the teeth of which mesh with an annular rack 52 formed in the under face of the fixed disk or spider frame 25. As the intermediate drum 27 and driver 110 frame secured thereto are rotated the engagement of the pinions 51 with the annular rack 52 will rotate the various disks 42 at the proper rate of speed.

Since the driving disks 42 and cooperating blocks 43 serve not only to drive the inner carriers, but also to support the same, it is unnecessary that the shoe or shoes 26 at the outer ends of the inner carriers support the weight of the carriers, and it 130

should be noted that in Figs. 1 and 4 the annular bearing surface 53 is formed as an annular groove with the lower portion of the groove cut away as at 54. This may be desirable because if the shoes 26 support the weight of the inner carriers, the blocks 43 might in some cases be held out of engagement with the driving disks 42, which is not desired. It will therefore be understood that in the construction shown in Figs. 1 and 4, the shoes 26 serve to take the outward thrust of the inner yarn carriers, due to centrifugal force, and that they serve also to keep the outer ends of the carriers from lifting up under the driving action of the disks 42; and they further serve to maintain the inner carriers properly seated upon the driving disks, but they do not need to support the weight of the inner carriers.

The traversing arms 46 may be operated as usual by a shoe secured to each arm, and which slides in the serpentine groove 55 formed in the inner face of the fixed outer drum 56 rigidly secured to the supporting table 10. The swinging movement imparted to the traversing arms 46 should be sufficient to depress the lower strand of yarn 45 to the position shown in dotted lines in Fig. 4, where it will be noted that this strand lies below the lower edge of the block 43, so that it may enter one of the notches 49 of the rotating disk without engaging the block 43, and as the strand of yarn passes the inner end of the inner carrier it is held out of engagement with the guides of the inner carrier and the yarn mass 21 of the inner carrier by the yarn spacing disk 57.

It is found that the sliding shoes 26 work extremely satisfactorily when they are formed of wood which has been soaked in oil, as the use of oil soaked shoes makes it unnecessary to supply any lubricant to the shoes or annular bearing surfaces other than that supplied by the oil of the wood, and if the temperature of the shoes rises, due to friction, the heat will drive out just enough oil to furnish the desired lubrication. This is important because it has been found difficult heretofore to keep the annular groove or runway that supports the outer end of the inner yarn carrier properly lubricated, without causing the oil to accumulate at the vertical slots 47 where it will soil the outer strands of yarn.

Since the notched driving disks 42 rotate against the bearing surface of the blocks 43, it is found very desirable to form these blocks of wood that has been treated with oil, as the oil treated wood will lubricate the face of the driving disks sufficiently to permit them to rotate smoothly against the blocks, while the wood will not supply enough oil to soil the inner strands of yarn passing thru the notches 49, and the notched

disks 42 are preferably formed of hardened steel. When oil treated wood is employed as a bearing element it is important that the bearing surface which it engages be smooth and highly polished. The bearing surface 53 against which the wooden shoes 26 slide should be highly polished, as should also the block engaging face of the disks 42.

The novel means herein described for supporting and driving the inner yarn carriers may be easily applied to the type of inner yarn carriers now in use. That is the present invention may be readily and inexpensively installed in machines now in actual use as well as in new braiding machines. This is due to the fact that the frames of the inner yarn carriers have been commonly provided heretofore with spaced laterally disposed slots in which the wheels 70 rotate that project into the annular groove of the outer drum, and it is a simple matter to remove these wheels and substitute therefor the shoes 26 of the present invention which may be secured in the slots of 80 the inner yarn carriers by screws 58.

Likewise the frames of the inner yarn carriers used heretofore have been provided with a vertical slot in which a driving roller 95 is mounted. It is a simple matter to remove the driving roller from the inner yarn carriers now in use and secure to these carriers the block 43 of the present invention, which is provided with a reduced portion 59 that is adapted to fit the slot just mentioned and may be secured therein by the screws 60.

In some embodiments of the invention it may be desirable to position the supporting block and cooperating driving disk of each inner carrier, so that these cooperating elements will support the entire or the greater portion of the weight of the inner carrier, and in Fig. 2 a modified construction is shown in which the driving disk 61 is disposed below the inner carrier frame 62 at a point sufficiently near the inner end of the carrier to support its inner end, and the cooperating block 63 is secured to the inner carrier frame in position to rest upon the driving disk 61 and the upper face of this block is cut away as at 64 to clear the inner yarn mass 65. As a result of this construction the supporting roller 22 shown in Figs. 1 and 4 at the inner end of the carrier may be omitted since the carrier may be supported at its outer end by the shoe 26 sliding in the annular groove 66, and at its inner end by the cooperating driving disk 61 and block 63.

In Fig. 3 a further modification of the invention is shown in which one driving disk 67 cooperates with a bearing block 68 to support the outer end of the inner yarn carrier 69, while the inner end of this car-

rier is supported by a second driving disk 70 which cooperates with a bearing block 71. In this construction, as in Fig. 2, it is unnecessary to provide a supporting roller 22 at the inner end of the inner carrier. It will be understood that in Fig. 3 the driving disks 67 and 70 are rigidly secured to and are rotated by the driving shaft having the bevel gear 72 secured to its inner end, 10 and the driving disk 70 may be somewhat smaller in diameter than the disk 67, since it travels thru a smaller circle as the inner carrier travels about the axis of the braiding machine.

15 In each of the constructions shown, the outer strands of yarn pass between the driving disks and cooperating blocks without being pinched, and the shoes at the outer end of the inner carriers slide smoothly 20 along the annular bearing surface of the revolving drum and over the vertical slots without any thumping or hammering effect.

What is claimed is:—

1. In a braiding machine, the combination of a revolving drum having an annular bearing surface facing the axis of the machine, inner yarn carriers, a driver for the inner carriers, means for rotating the driver about the axis of the machine, driving disks 25 carried by said driver, blocks secured to the carriers and having bearing surfaces that rest upon the driving disks to cause these disks to support and drive the inner carriers, and thrust means extending from the 30 inner carriers into engagement with said bearing surface.

2. In a braiding machine, the combination of a revolving drum having an annular bearing surface facing the axis of the machine, inner yarn carriers supported within 40 the revolving drum to travel in a horizontal plane, a driver for the inner carriers, means for rotating the driver about the axis of the machine, driving disks carried by said driver, blocks secured to the inner carriers and having concave bearing surfaces that rest upon the driving disks to cause the 45 disks to support and drive the inner carriers, and thrust means extending from the inner carriers into engagement with said bearing surface.

3. In a braiding machine, the combination of a revolving drum having an annular bearing surface facing the axis of the machine, inner yarn carriers each constructed 55 to support a yarn mass, a race-way for supporting the inner end of the carriers, a driver for the inner carriers, means for rotating the driver, driving disks carried by the driver, blocks secured to the carriers and constructed to rest upon the disks to 60 drive the carriers and support their outer ends, and thrust means extending from the inner carriers into engagement with said bearing surface.

4. In a braiding machine, the combination of a revolving drum having an annular bearing surface facing the axis of the machine, inner yarn carriers supported to travel in an annular path inside of the revolving drum, a driver for the inner carriers, means for rotating the driver, driving disks carried by the driver, blocks secured to the carriers and having concave bearing faces that rest upon and partly embrace the disks to support the carriers and form a positive driving connection between the driver and carriers to prevent the latter from running ahead of their respective driving disks, and thrust means extending from the inner carriers into engagement with said bearing surface.

5. In a braiding machine, the combination of a revolving drum having an annular bearing surface facing the axis of the machine, inner yarn carriers mounted to travel in a circular path within the revolving drum, a driver for the inner carriers, means for rotating the driver, driving disks rotatably mounted upon the driver, means actuated by the movement of the driver for positively rotating the disks, blocks secured to the carriers and having bearing surfaces that rest upon the driving disks to form a positive driving connection between the driver and inner carriers, and thrust means extending from the inner carriers into engagement with said bearing surface.

6. In a braiding machine, the combination of a revolving outer drum having an annular bearing surface facing inwardly, inner yarn carriers mounted to travel in a circular path within the revolving drum, a driver frame for the inner carriers, means for rotating the driver frame, notched driving disks rotatably mounted upon the driver frame, means for positively rotating the disks at a speed to cause the strands of yarn from the different outer yarn carriers to enter different notches of a driving disk, blocks secured to the carriers and having bearing surfaces that are engaged by the disks to drive the carriers, and thrust means extending from the inner carriers into engagement with said surface.

7. In a braiding machine, the combination of a revolving outer drum, inner yarn carriers supported to travel in a circular path within the revolving drum, a driver frame for the inner carriers, means for rotating the driver frame, notched driving disks rotatably mounted upon the driver frame, means for positively rotating the disks at a speed to cause the strands of yarn from the different outer yarn carriers to enter different notches of a driving disk, and blocks secured to the inner carriers and having bearing surfaces that are engaged by the disks to drive the inner carriers.

8. In a braiding machine, the combination

of a revolving outer drum, inner yarn carriers supported to travel in a circular path within the revolving drum, a driver frame for the inner carriers, means for rotating the driver frame, a pair of bearing blocks secured to each carrier to support the carrier at different points radially thereof, and driving disks mounted upon the driver frame in radially spaced relation from the axis of the machine to engage the bearing blocks so that the disks support and drive the inner carriers.

9. In a braiding machine, the combination of a revolving outer drum having an annular bearing surface at its inner face, inner yarn carriers supported to travel in a circular path within the revolving drum, a driver frame for the inner carriers, means for rotating the driver frame, a pair of bearing blocks secured to each inner carrier at different distances from an end thereof, driving disks mounted upon the driver frame in radially spaced relation from the axis of the machine to engage the bearing blocks so that the disks support and drive the inner carriers, means for positively rotating said disks, and thrust means extending from the inner carriers into engagement with said bearing surface to hold the carriers in place upon said disks.

10. In a braiding machine, the combination of a revolving outer drum having an annular bearing surface at its inner face, inner yarn carriers supported to travel in a circular path within the revolving drum, a driver frame supported to rotate about the axis of the braiding machine, means for rotating the driver frame, driving disks carried by the driving frame, bearing blocks secured to the inner carriers and constructed to rest upon the disks to cause the latter to support and drive the inner carriers, and sliding shoes projecting from the inner carriers into engagement with said bearing surface to hold the carriers in position upon the driver disks and each shoe having a relatively long bearing face that slides against said surface.

11. In a braiding machine, the combination of a revolving outer drum having an annular bearing surface at its inner face, inner yarn carriers supported to travel in a circular path within the revolving drum, a driver supported to rotate about the axis of the braiding machine, means for rotating the driver, driving disks carried by the driver, bearing blocks secured to the inner carriers and having bearing faces which the disks engage to drive the inner carriers, and each carrier having a pair of spaced shoes extending from its outer end into sliding engagement with said annular bearing surface.

12. In a braiding machine, the combination of a revolving outer drum having an

annular bearing surface formed at its inner face, inner yarn carriers supported to travel in a circular path within the revolving drum, means for driving the inner carriers, and shoes formed of wood to take the centrifugal thrust of the inner carriers and extending from the outer ends of the carriers to slide against said bearing surface.

13. In a braiding machine, the combination of a revolving outer drum having an annular bearing surface formed at its inner face, inner yarn carriers supported to travel in a circular path within the revolving drum, means for driving the inner carriers, and each inner carrier having an oil treated wooden shoe extending from the carrier into sliding engagement with said annular bearing surface to receive the centrifugal thrust of the carrier and forming a self-lubricating slide.

14. In a braiding machine, the combination of a revolving outer drum having an annular groove in its inner face, inner yarn carriers supported to travel in a circular path within the revolving drum, means for driving the inner carriers, and each inner carrier having an oil treated wooden shoe extending from the carrier into the annular groove to slide therein and forming a self-lubricating slide.

15. In a braiding machine, in combination, inner and outer yarn carriers supported to travel in opposite directions about the axis of the braiding machine, means for driving the inner and outer carriers, a supporting frame for the inner carriers having an annular bearing surface, and shoes upon the inner carriers that slidably engage said bearing surface and constructed of oil soaked wood to form self-lubricating slides.

16. In a braiding machine, in combination, outer and inner yarn carriers supported to travel in circular paths about the axis of the braiding machine, means for driving the outer carriers in one direction, means for driving the inner carriers in the opposite direction, including driving disks that travel in a circular path about the axis of the braiding machine, and bearing blocks upon the inner carriers positioned to be engaged by said disks to cause the latter to propel the inner carriers, said bearing blocks being formed of oil-treated wood to present a self-lubricating bearing surface to each disk.

17. In a braiding machine, in combination, outer and inner yarn carriers supported to travel in circular paths about the axis of the braiding machine, means for driving the outer carriers in one direction, a revolving driving frame for driving the inner carriers in the opposite directions, driving disks journaled upon said driving frame, a bearing block upon each inner

yarn carrier positioned to be engaged by a disk to cause the latter to propel an inner carrier, means for positively rotating each driving disk relatively to its bearing block, and said bearing blocks being formed of oil treated wood to provide a self lubricating bearing surface to the periphery of the operating disk.

18. In a braiding machine, in combination, a set of outer yarn carriers supported to be revolved in one direction, a set of inner yarn carriers supported to be revolved in the opposite direction, a bearing block secured to each inner yarn carrier and having a concave bearing surface, rotating disks adapted to engage the concave bearing surface of said blocks to drive the inner yarn carriers, and means for supporting and driving said disks.

19. In a braiding machine, in combination, outer and inner yarn carriers supported to travel in opposite directions about the axis of the braiding machine, a revolving frame for supporting the inner yarn carriers, rotating disks upon said frame, a bearing block upon each inner carrier having a concave bearing surface adapted to rest upon a disk to support its inner carrier, and means for revolving said frame.

20. In a braiding machine, the combination of a revolving drum having an annular bearing surface, inner and outer yarn carriers supported to revolve about the axis of the braiding machine, a driver frame for the inner yarn carriers, means for rotating said frame, driving disks carried by the driver frame, blocks secured to the inner carriers and having bearing surfaces that are engaged by said disks as the latter drive

the inner carriers, and guiding means upon the inner carriers and engaging said bearing surface.

21. In a braiding machine, the combination of a revolving drum having an annular bearing surface, outer yarn carriers mounted upon said drum to rotate therewith, inner yarn carriers mounted to travel in an annular path in the opposite direction to the outer yarn carriers, means for supporting the inner yarn carriers so that the strands of outer yarn may pass freely between the inner carriers and their supporting means, including a bearing block upon each inner carrier having a lower bearing surface, and rotating disks supported below said blocks to engage said bearing surface and support the inner carriers.

22. In a braiding machine, in combination, outer and inner yarn carriers supported to travel in circular paths about the axis of the braiding machine, means for driving the outer carriers in one direction, a revolving driving frame for driving the inner carriers in the opposite direction, a driving disk for each inner carrier journaled upon said driving frame, a bearing block upon each inner yarn carrier positioned to be engaged by a disk to cause the latter to propel an inner carrier, means for rotating each driving disk relatively to its cooperating block to promote the passage of outer strands of yarn between them, and one of said cooperating driving elements for each inner carrier being formed of oil treated wood.

In testimony whereof, I have signed my name to this specification.

OTTO A. FREDERICKSON.
